UNITED STATES PATENT OFFICE.

CHARLES A. PILQUIST, OF NESS CITY, KANSAS.

OIL-BURNER.

1,277,642.

Specification of Letters Patent. Patented Sept. 3, 1918.

Application filed October 31, 1917. Serial No. 199,546.

To all whom it may concern:

Be it known that I, CHARLES A. PILQUIST, a citizen of the United States, residing at Ness City, in the county of Ness and State 5 of Kansas, have invented certain new and useful Improvements in Oil-Burners, of which the following is a specification.

This invention relates to oil burners, and is somewhat similar to the burner disclosed 10 in my U. S. Letters Patent No. 1,232,392, dated July 3, 1917; the chief difference being that the present burner is more especially adapted to the consumption of crude oil, although the lighter hydrocarbon oils, 15 such as kerosene, distillate, etc., can also be used economically.

In carrying out the invention, it will be understood that the essential features thereof may be changed within the spirit and 20 scope of the claims, and in order that the invention may be fully understood, reference will now be made to the accompanying drawing, in which:

Figure 1 is a central, vertical, sectional view of a burner in the fire box of a stove.

Fig. 2 is an inverted, plan view of a flame spreader forming a part of the invention.

Fig. 3 is a plan view of an oil spreader.

Fig. 4 is an inverted plan view of the oil 30 spreader.

A designates the fire box of a stove, B the grate thereof, C a sheet metal plate covering the grate B, and D asbestos cement laid to the desired thickness upon the plate 35 C to prevent the passage of air through the grate, except at its central portion where an air supply pipe 1, extends upwardly a suitable height.

3 designates an annular trough-shaped 40 generator encircling the air pipe 1 and having its bottom portion slightly embedded in the asbestos cement D.

5 designates an oil spreader consisting 45 of a circular plate which is crowned as disclosed by Fig. 1, to distribute the oil uniformly over the upper surface thereof as it flows from a supply pipe 7. The oil spreader 5 is provided at its underside with legs 9, having shoulders 10 to rest upon the inner 50 annular margin of the generator 3. The legs 9 are provided with depending guides 11, which enter the central opening in the generator 3 and also secure the oil spreader 5 from lateral displacement when in posi-

tion upon said generator. Lugs 14 project 55 upwardly from the top of the oil spreader 5 to support a flame spreader 16, spaced slightly above said oil spreader to avoid obstructing the flow of oil from the discharge end of the pipe 7. The flame spreader 16 60 consists of a circular plate having a vertically depending marginal flange 18, loosely embracing the vertically depending marginal flange 5 of the oil spreader 5, which latter has peripheral spacing members 20 65 that serve to center the flame spreader thereon.

In practice the bottom of the generator 3 is provided with a wick 24 and the oil pipe 7 is connected to a suitable source (not shown) and provided with a valve (not shown) for controlling the flow of oil therethrough. As the oil discharges from the pipe 7, it overflows the oil spreader 5 in all directions and runs down into the generator 75 3, where it saturates the wick 24. The saturated wick is then ignited and as the resultant flame ascends to escape through the annular opening 30 between the upper margin of the generator 3 and the lower edge 80 of the flange 18, it impinges against said flange 18 and the margin of the oil spreader 5, thus heating the same to a sufficient degree to convert the oil into gas before reaching the margin of said oil spreader 5. As the 85 gas thus generated in the chamber 32 between the oil spreader 5 and the flame spreader 16, passes downward through the spaces between the margin of said oil spreader 5 and the flange 18, it becomes 90 thoroughly mixed with the air supplied through the pipe 1, thus forming a highly combustible mixture, the flame from which is spread by the flame spreader 16 and passes from the opening 30 in a continuous 95 annular sheet which impinges against the walls of the fire box A, and thus quickly heats the same to a high degree. The air becomes heated as it ascends through the pipe 1 and comes into contact with the oil spreader 5 and thus readily commingles with the highly heated gas discharged from the chamber between spreaders 5 and 16. As the oil supply pipe 1 is not exposed to the flame, it 100 does not become choked with soot or carbon. Should carbon form on the spreaders 5 and 16, they can be readily cleaned on removing them through the stove door. Should any 105

part of the burner become defective, it can be readily replaced by another part without discarding other members of the burner.

By only slightly crowning the top of the oil spreader 5, the flow of the oil is retarded sufficiently to permit it to become thoroughly vaporized in the gas chamber 32 after the spreaders 5 and 16 are heated, and hence there is no danger of unvaporized oil flowing into the generator 3.

Having thus described my invention, what I claim and desire to secure by Letters Patent, is:

1. In combination with a fire box, a sheet metal plate laid upon the grate in said fire box and having a central opening therein, an air supply tube extending upwardly from the central opening in said plate, an annular trough-shaped generator arranged above the plate, a wick in the bottom of said generator, an oil distributer superimposed on said generator and provided with a crowned upper surface, an oil supply pipe communicating with the upper surface of the oil distributer, a flame spreader having a depending marginal flange loosely embracing the margin of the oil distributer and spaced from the top of the generator to leave an opening, for the purpose described, and fire proof material

covering the sheet metal plate and surrounding the air supply tube and the generator, for the purpose specified. 30

2. An oil burner comprising a centrally disposed air tube, an annular trough-shaped generator of V-shaped cross section separable from but embracing said air tube, an oil spreader plate having depending legs engaging the upper inner margin of said generator, the top of said plate being slightly crowned, a vertically depending marginal flange on the oil spreader plate having peripheral spacing lugs, a flame spreader plate superimposed on the oil spreader plate but spaced therefrom to leave an intervening gas chamber, a vertically depending marginal flange on said flame spreader plate loosely embracing the spacing lugs on the flange of the oil spreader plate, and an oil supply pipe extending upwardly through the central portion of the oil distributer plate, substantially as described. 35 40 45

In testimony whereof I affix my signature, in the presence of two witnesses.

C. A. PILQUIST.
